UNITED STATES PATENT OFFICE.

FREDERICK F. MACLEAN, OF SYRACUSE, NEW YORK, ASSIGNOR, BY MESNE ASSIGNMENTS, OF ONE-HALF TO LUCIUS G. LACY, OF SYRACUSE, NEW YORK.

HEADLIGHT FOR MOTOR-VEHICLES.

1,292,840.

Specification of Letters Patent.

Patented Jan. 28, 1919.

Application filed February 17, 1916, Serial No. 78,982. Renewed October 24, 1918. Serial No. 259,571.

To all whom it may concern:

Be it known that I, FREDERICK F. MACLEAN, a citizen of the United States of America, and resident of Syracuse, in the county of Onondaga, in the State of New York, have invented new and useful Improvements in Headlights for Motor-Vehicles, of which the following, taken in connection with the accompanying drawings, is a full, clear, and exact description:

This invention relates to certain improvements in headlights for motor vehicles and is somewhat similar to that set forth in my pending application, Serial No. 11,677, filed 15 March 3, 1915, in that it makes use of a turning connection between the lamp base and socket for use in connection with a lamp bulb similar to that set forth in my Patent No. 1,146,268, issued July 13, 1915, in which 20 a portion of the bulb is coated to prevent excessive glare in the eyes of approaching horses, pedestrians and drivers of other vehicles.

In lamps of this character, it is necessary 25 to not only provide for the proper focusing of the light, but also to enable the bulb to be adjusted independently of the focus adjustment to bring the coated portion of the bulb at the proper side of the focal axis, and the 30 main object of my present invention is to provide for this adjustment without in any way affecting the focus or intensity of the light.

One of the specific objects is to simplify, 35 and at the same time, to increase the efficiency of the turning connection between the base of the lamp and bulb in holding the bulb against accidental turning and permitting it to be readily turned by hand to the 40 desired position to properly position the coating with reference to the focal axis of the reflector with which the lamp is usually used.

Other objects and uses will be brought out 45 in the following description.

In the drawings—

Figure 1 is a side elevation of my improved headlight showing a portion of the reflector and lamp support in section. 50 Fig. 2 is a side elevation, partly in section, of the lamp base and socket.

Fig. 3 is a transverse sectional view through the connection between the lamp base and socket.

Fig. 4 is a perspective view of the de-

tached ring by which the lamp base is connected to the socket.

Fig. 5 is a perspective view of the detached lamp base and adjacent portion of the bulb.

Fig. 6 is a transverse sectional view, similar to Fig. 3, showing a modified form of connecting ring.

Fig. 7 is a perspective view of the detached ring shown in Fig. 6.

The headlight comprises a reflector —1— and a co-axial lamp comprising a bulb —2— having a suitable base —3— and a socket —4—, the latter being provided with an externally threaded portion —5— screwing 70 into an internally threaded hub —6— of the reflector —1—.

The lamp is provided with any suitable electrically incandescent filament —2'— adapted to be connected in the lamp circuit 75 through the medium of the usual "center-and-rim" contacts, commonly used for producing a light of definite intensity from a storage battery or other comparatively low voltage source of electric energy, not shown.

The lamp base is provided with a metal sleeve or casing having an annular groove —7— for receiving a split ring —8— which is fitted to turn therein and is held against endwise movement by the portions of the 85 base —3— at the ends of the annular groove —7—, thus permitting the bulb to be turned in the ring about its axis without changing the focus or intensity of the light.

As shown in Figs. 1 to 5, inclusive, the 90 ends of the ring at the division are bent slightly inwardly to form nibs —8'— which, under the tension of the ring, are adapted to frictionally engage the periphery of the base —3— within the groove —7—, thereby 95 preventing accidental turning of the lamp bulb when once adjusted by hand, it being understood that although the ring —8— is frictionally engaged with the periphery of the lamp base —3—, the bulb may be readily 100 turned by hand within certain limits, as hereinafter described.

The means for limiting the turning movement of the base —3— in the ring consists of a stop pin —9— projecting radially from 105 the base —3—, and preferably midway between the ends of the groove —7—, as shown more clearly in Fig. 5.

The ring —8— is provided with a circumferentially extending slot —10— for receiv-

ing the pin —9—, said slot terminating short of the ends of the ring so that the portions of the ring at the ends of the slot will co-operate with the pin —9— to limit the turning movement of the lamp base in said ring.

This ring is detachably interlocked with the adjacent end of the lamp socket —4— through the medium of a "bayonet lock" consisting of diametrically opposite radial pins —11— on the ring and annular slots —12— in the socket —4— so that when the lamp base with the ring —8— thereon is inserted in the socket and the ring interlocked with the socket in the manner described, the pin —9— will be held in its interlocking engagement by the tension produced by the center contacts, one of which is usually spring-tensioned toward the other in a manner not necessary to herein illustrate or describe, because such contacts are well known in this art.

In Figs. 6 and 7, I have shown a modified form of ring —13— of slightly greater circumferential length than a half circle adapted to fit within the annular groove —7— to turn therein, and is tensioned so as to frictionally bind upon the base —3— to prevent accidental turning, the ends of the ring being spaced some distance apart to receive between them the radially projecting pin —9— on the lamp base and to co-operate therewith for limiting the turning movement of the lamp bulb when the ring is interlocked with the socket —4—.

The screw connections —5— and —6— between the socket and hub of the reflector enable the lamp to be properly adjusted relatively to the focus of the reflector, but when once adjusted relatively to said focus, it re-

mains in that position except for the rotary adjustment of the bulb in the ring —8—, the purpose of which is simply to properly position the coating, as —14—, on the bulb with reference to the focal axis of the reflector without in any way affecting the focusing or intensity of the light.

What I claim is:

1. The combination with a reflector, an incandescent electric lamp base and a lamp socket for receiving the same, of a split ring rotatably mounted on the lamp base and provided with inturned nibs frictionally engaging the periphery of the base, means for holding said ring against axial movement relatively to the lamp base, and interlocking connections between the ring and socket.

2. The combination with a lamp base and a socket for receiving the same, said base being provided with an annular groove, of a split ring fitted in said groove to turn therein, means for limiting the turning movement of the ring relatively to the base, and detachable interlocking connections between the ring and socket.

3. The combination with a lamp base and a socket for receiving the same, of connections between said base and socket for permitting the lamp to be turned relatively to the socket without changing the focus or intensity of the light, and means for limiting the turning movement of the base relatively to the socket.

In witness whereof I have hereunto set my hand this 15th day of February, 1916.

FREDERICK F. MACLEAN.

Witness:

H. E. CHASE.
